DESIGN FOR A COMBINED TABLE COOKING STOVE AND SUPPORT

William J. Russell and Marion C. Yerigan, Mansfield, Ohio, assignors to Westinghouse Electric & Manufacturing Company, East Pittsburgh, Pa., a corporation of Pennsylvania

Application January 18, 1939, Serial No. 82,420

Term of patent 7 years

To all whom it may concern:

Be it known that we, William J. Russell and Marion C. Yerigan, citizens of the United States, residing at Mansfield, in the county of Richland and State of Ohio, have invented a new, original, and ornamental Design for a Combined Table Cooking Stove and Support, of which the following is a specification, reference being had to the accompanying drawing, forming a part thereof in which: the stove and support being in closed position, the concealed end of the stove and support being like the end illustrated, this figure being drawn on a smaller scale than Fig. 2.

Fig. 2 is a perspective view, taken in a similar way, of the combined table cooking stove and support in extended position.

We claim:

The ornamental design for a combined table cooking stove and support, substantially as shown and described.

WILLIAM J. RUSSELL.
MARION C. YERIGAN.
